UNITED STATES PATENT OFFICE.

JOSEPH W. C. MEIKLE, OF BALTIMORE, MARYLAND.

DESIGN FOR A GAME-BOARD.

SPECIFICATION forming part of Design No. 32,889, dated June 26, 1900.

Application filed May 23, 1900. Serial No. 17,764. Term of patent 3½ years.

To all whom it may concern:

Be it known that I, JOSEPH W. C. MEIKLE, a citizen of the United States, residing at Baltimore, in the State of Maryland, have invented a certain new and original Design for Game-Boards, of which the following is a specification.

This invention relates to a new design for game-boards.

10 In the accompanying drawings, Figure 1 is a plan view; and Fig. 2 is a section on line x x , Fig. 1.

Referring to said figures by numerals of reference, 1 is a rectangular base having a flange 2 therearound, as shown, and a groove 3 extends around the inner edge of this flange. A rectangle 4 is outlined in one corner of the base 1 by means of lines 5, as shown, and this rectangle is provided with grooves 6, which 20 extend along the diagonals and diameters

thereof. It will be seen that the diameter and diagonal grooves upon two sides of the square open into the groove 3. All of the diagonal and diameter grooves are connected at the center by a circular recess 7, within which is 25 located a flange 8 in the form of the letter **C**, the opening between the ends of which is located at a point opposite one of the walls of the recess.

Having thus fully described my invention, 30 what I claim as new, and desire to secure by Letters Patent, is—

The design for a game-board substantially such as herein shown and described.

In testimony whereof I affix my signature 35 in presence of two witnesses.

JOSEPH W. C. MEIKLE.
